UNITED STATES PATENT OFFICE

CHARLES H. PATTEN, OF PROVIDENCE, RHODE ISLAND, ASSIGNOR TO REX MANUFACTURING COMPANY, OF PROVIDENCE, RHODE ISLAND, A CORPORATION OF RHODE ISLAND

POCKET LIGHTER

Application filed February 18, 1928. Serial No. 255,299.

This invention relates to a pocket lighter of the type using pyrophoric material and a friction wheel for ignition purposes; and has for its object to provide a construction for mounting the different operating parts of the lighter so as to positively position these parts with reference to another to insure an accurate cooperation thereof.

A further object of the invention is to fold inwardly portions of the top plate to form an increased bearing for the different operating parts as they extend through the top plate into the fuel tank to better support the same and afford an increased soldering surface.

A still further object of the invention is the aligning of the different operating parts carried by the fuel tank so that the tank may be made exceedingly thin to take up the minimum amount of room in the vest pocket of the user.

With these and other objects in view, the invention consists of certain novel features of construction, as will be more fully described, and particularly pointed out in the appended claims.

In the accompanying drawings:

Fig. 1 is a side elevation of the lighter on an enlarged scale.

Fig. 2 is a perspective view of the top plate.

Fig. 3 is a perspective view of the top plate inverted and looking at the under side thereof.

Fig. 4 is a side elevation of the pyrophoric tube.

Fig. 5 is a central sectional view through the same taken at right angles to the position of the tube shown in Fig. 4.

Fig. 6 is a side elevation of the hinge post for mounting the snuffer arm.

Fig. 7 is a central sectional view of the same.

Fig. 8 is a side elevation of the wick tube.

Fig. 9 is a fragmental view with the top plate in section showing the different parts of the operating mechanism mounted therein.

Fig. 10 is a central sectional view through the lighter with the parts in assembled position.

Fig. 11 is a fragmental detail partly in section showing the pyrophoric tube mounted in the top plate.

Fig. 12 is an elevation of the lighter in full size showing the actual thickness thereof.

It is found desirable in the construction of pocket lighters to provide a construction by which the parts may be easily assembled and held in the definite fixed relation in which it is desired that they be soldered in position so that the hinged snuffer arm will positively close over the wick to seal the same against evaporation and a guard thereon will protect the friction wheel, which I have accomplished by forming an integral collar about the opening through which the tubes or posts extend to guide and better support them, and I have aligned the operative parts of the lighter so that the same may be formed extremely thin to take up the minimum amount of space in the vest pocket of a user; and the following is a detailed description of the present embodiment of the invention illustrating one construction by which these advantageous results may be obtained:

With reference to the drawings, 15 designates a tubular body portion of the fuel tank which has suitably secured thereto a bottom plate 16 having a fuel-filling opening 17 closed by a stopper 18 having a pocket 19 for extra flints, if desired. The top plate 20 has openings 21 and 22 therein which are formed by cutting the stock of the plate and bending the same inwardly to form collar bearings 23 and 24 which are generally cylindrical in shape and of a size to receive different operating parts of the lighter as will be hereinafter explained.

The pyrophoric tube 25 extends through the opening 20 and is supported perpendicularly to the top plate by the inwardly-extending collar 24 thereabout, while a shoulder 26 thereon seats against the top plate. Pyrophoric material 27 is located in the tube and pressed by spring 28 into engagement with the friction wheel 29 fixed to a suitably mounted shaft 37 and having a thumb wheel 36 for manual rotation. The tension on the spring may be suitably adjusted by means of a screw 30 having threaded engagement

at 31 with the tube 25 which terminates short of the bottom plate 16. A sleeve 32 embraces the tube 25 and extends the remaining portion of the distance between the tube 25 and the bottom plate and forms a recess 33 for the reception of the head 34 of this adjusting screw. This sleeve is slightly enlarged as at 35 to embrace the inwardly-extending collar portions of the top plate to support the same and force and hold it firmly in engagement with the tube in its position in the top plate.

A wick tube 38 shouldered as at 39 to seat against the top plate is positioned through the opening 21 and supported by collar portions 23 thereabout. Through this wick tube there extends a wick 40 which is in such close proximity to the friction wheel that sparks caused by the rotation thereof against the pyrophoric material 27 causes ignition of the wick.

A hinge post 41 extends through the opening 22 and is provided with a bifurcated portion or ears 42 between which is pivoted the snuffer arm 43 carrying a cap 44 to close over the wick 40 and extinguish the same and also a guard 45 to extend over the friction wheel to protect the same from contact with the pocket as the device is carried by the user. A plunger 46 causes the square end 47 of the snuffer arm to be resiliently retained in any of three desired positions according to which of its three generally right-angularly disposed surfaces are in contact therewith. This plunger is resiliently pressed into engagement with the hinge portion of the arm by a spring 48, as will be clearly apparent.

The snuffer arm, wick and the friction wheel are all mounted in substantially the same line, whereby the fuel tank may be made extremely thin. In fact, I have found that by the arrangement disclosed I can make the same approximately 300 thousandths of an inch which is less than one-quarter of the width of the lighter body, which thickness is such that there is no bulk to bulge the pocket or cause any discomfort in carrying the same by the user.

By providing the collar portions extending from the top plate the pyrophoric tube, wick tube, and hinge post assume a definite relation, all perpendicular to the top plate in which position they may be readily soldered so that the hinge arm will in all assemblies of the parts properly cover the wick and guard the friction wheel.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

65 1. A pocket lighter comprising a fuel tank

having a body portion with a bottom plate and a top plate having a plurality of aligned openings therein with portions of the stock of said plate extending inwardly at right angles thereto about said openings to form 70 collars thereabout, a pyrophoric tube extending through one of said openings, a snuffer arm hinge post extending through another of said openings, and a wick tube extending through another of said openings, the parts 75 in each of said openings having a shoulder to engage said top plate, and each of the parts in said openings being held in definite relation to each other by the collars on said plate about said openings.

2. A pocket lighter comprising a fuel tank having top and bottom plates, the top plate having an opening therein with the stock of the plate turned inwardly to form a collar portion about said opening, a pyrophoric tube 85 extending through said opening and supported by said collar and of a length to be shorter than the tank and spaced from the bottom plate, a sleeve embracing said tube and collar and extending to said bottom plate, 90 and a threaded member in said sleeve in the portion between said tube end and bottom plate.

3. A pocket lighter comprising a fuel tank having top and bottom plates, the top plate 95 having an opening therein with the stock of the plate turned inwardly to form a collar portion about said opening, a pyrophoric tube extending through said opening and collar and of a length to be shorter than the tank 100 and spaced from the bottom plate, a sleeve embracing said tube and collar to force said collar tightly into contact with said tube.

4. A pocket lighter comprising a fuel tank having top and bottom plates, the top plate 105 having an opening therein with the stock of the plate turned inwardly to form a collar portion about said opening, a pyrophoric tube extending through said opening and collar and of a length to be shorter than the tank 110 and spaced from the bottom plate, a sleeve embracing said tube and collar to force said collar tightly into contact with said tube, said sleeve extending to said bottom plate and leaving a space between the end of said tube and bottom plate, and a threaded member adjustable in said tube and having its head in said space.

5. A sheet metal top for a pocket lighter having a plurality of aligned openings therein, each opening having an integral depending collar.

In testimony whereof I affix my signature.
CHARLES H. PATTEN.
